UNITED STATES PATENT OFFICE

PHINEAS B. MYERS, OF NEW YORK, N. Y.

DESIGN FOR A PAPER BOX.

SPECIFICATION forming part of Design No. 28,640, dated May 17, 1898.

Application filed February 23, 1898. Serial No. 671,389. Term of patent 14 years.

To all whom it may concern:

Be it known that I, PHINEAS B. MYERS, of New York, (Brooklyn,) county of Kings, and State of New York, have invented and produced a new and original Design for Paper Boxes, of which the following is a specification, reference being had to the accompanying drawing, which represents a perspective view of my newly-designed paper box.

The leading feature of my design consists of a box having a sloping top and two books supported upon such top, the whole being a conventionalized representation of a safe.

The rectangular box is provided with a paneled front a , paneled sides a' , and a paneled top rail a^2 . Upon the sloping top of the box are represented a pair of books b , the whole being a conventionalized representation of a safe.

What I claim is—

The design for a paper box, substantially as herein shown and described.

PHINEAS B. MYERS.
